UNITED STATES PATENT OFFICE

2,011,158

William L. Pearce, Houston, Tex.

Application August 16, 1934, Serial No. 740,079

5 Claims. (Cl. 255—61)

This invention relates to a drill.

An object of the invention is to provide a drill of the character described specially designed for drilling wells through earth formation, such as deep oil wells which pierce both hard and soft strata.

Another object of the invention is to provide a drill having side blades or cutters which are reduced in width from above downwardly, and the drill preferably terminates at its lower end in a pilot, the combination being such that a drill will be provided which will drill a comparatively straight bore through the various formations encountered.

15 Another object of the invention is to provide a drill of the character described having a novel arrangement of channels through which the drilling fluid may be conducted from the drill stem downwardly through the drill and delivered to the cutting blades or cutters so as to flush the same, to prevent the collection of the formation thereon, to keep the cutters cool and to flush out the bore.

With the above and other objects in view, the invention has particular relation to certain novel features of construction, arrangement of parts and use, an example of which is given in this specification and illustrated in the accompanying drawing, wherein:

30 Figure 1 shows a side view of the drill and Figure 2 shows an edge view partly in section. In the drawing, the numeral 1 designates the drill head which is preferably cylindrical and whose upper end is threaded, as at 2, for the connection of a drill stem or other driving member thereto.

40 Beneath the head and formed integrally therewith there is the main body 3 which is flattened, as shown, and is somewhat wider, transversely, than the diameter of the head. This body tapers downwardly in thickness and approximately midway between the head and the lower end of the body is reduced in width and formed with the oppositely curved side cutters 4, 4. The forward faces of these side cutters 4 are of a general concave contour as shown. The reduced portion 3' of the body terminates at its lower end in the oppositely curved side cutters 5, 5 of approximately the same shape as the cutters 4. These side cutters 4, 5 are preferably blade like in form and terminate in sharp transverse cutting edges although any selected design of cutters may be employed. Between the side cutters 5, 5 and extended beneath them there is a pilot 6 terminating in a diamond point 7.

2,611,193

WILHELMUS LUDWIGUS VAN DER KEMPEN, a member of the Dutch Parliament, has applied for a patent of the following description:

PATENT OFFICE

1934, Serial No. 740,079 (U.S. Pat. No. 2,055,611).

This pilot is of somewhat less transverse diameter than that of the reduced body portion 3'.

Extending from the upper end of the drill downwardly into the head 1 there is a relatively large bore 7 and leading downwardly from this bore and terminating within the contour of the forward faces of the blades 4, 4 are the channels 8, 8. The channels 8 have the branches 9, 9 leading downwardly from the inner sides thereof and terminating on opposite sides of the drill at the upper end of the pilot 6. These channels 8, 9 may be cheaply formed in the construction of the drill by forming grooves in the opposite sides of the body and then covering the grooves with the plates 10, 10, 11, 11 whose margins are countersunk into the body and are welded thereto, the upper ends of said channels 8 continuing on up through the head into the bore 7.

It is to be noted that the upper ends of the channels 8 merge together so that the material between them will present a sharp upwardly directed cutting edge 12 and similar sharp upwardly directing cutting edges 13, 13 will be provided between the branches 9 and the channels 8 as indicated in Figure 1, said cutting edges 12 and 13 thus offering slight interference to the drilling fluid being forced downwardly through said channels so as not to retard the velocity thereof.

On account of its length this type of drill will tend to follow a straight course and in that respect the drill will be assisted by the pilot 6; also on account of the distribution and arrangement of the cutting blades, the drill will very rapidly penetrate the formation encountered.

The drawing and description disclose what is now considered to be a preferred form of the invention by way of illustration only, while the broad principle of the invention will be defined by the appended claims. 35

What I claim is:

1. A drill comprising a drill head formed for the attachment of a drill stem thereto, a body formed integrally with the head and having upper side cutters, said body being reduced in width beneath said cutters, the reduced portion of the body terminating at its lower end in lower side cutters, said drill having channels leading downwardly therethrough and terminating above the upper side cutters and also having branch channels leading from the first mentioned channels and terminating above the lower side cutters. 45 50

2. A drill comprising a drill head formed for the attachment of a driving member thereto, a body formed integrally with the head and having side cutters, said body being reduced in width 55

- beneath said side cutters and extended downwardly, and terminating at its lower end in side cutters, said drill having downwardly diverging channels therethrough terminating in openings above the upper side cutters, said channels having downwardly converging branch channels which terminate above the lower side cutters.
3. A drill comprising a drill head formed for the attachment of a driving member thereto, a body formed integrally with the head and having side cutters, said body being reduced in width beneath said side cutters and extended downwardly, and terminating at its lower end in side cutters, said drill having downwardly diverging channels therethrough terminating in openings above the upper side cutters, said channels having downwardly converging branch channels which terminate above the lower side cutters, and a pilot at the lower end of the reduced portion of the body located between the lower side cutters.
4. A drill comprising a drill head formed for the attachment of a driving member thereto, a flattened body formed integrally with said head and having side cutters, said body being reduced in width beneath said cutters and extended downwardly, said reduced portion terminating in cutters at its lower end, said drill having a bore

leading downwardly from the upper end thereof, and having diverging channels leading downwardly from the bore which have discharge openings above the upper side cutters, downwardly converging branch channels leading from the said diverging channels and terminating in discharge openings adjacent the lower end of the reduced portion of the head.

5. A drill comprising a drill head formed for the attachment of a driving member thereto, a flattened body formed integrally with said head and having side cutters, said body being reduced in width beneath said cutters and extended downwardly, said reduced portion terminating in cutters at its lower end, said drill having a bore leading downwardly from the upper end thereof, and having diverging channels leading downwardly from the bore which have discharge openings above the upper side cutters, downwardly converging branch channels leading from the said diverging channels and terminating in discharge openings adjacent the lower end of the reduced portion of the head, and a pilot formed integrally with and extended beneath the reduced portion of the body, said pilot having a transverse diameter less than that of the reduced portion of the body.

WILLIAM L. PEARCE.
